UNITED STATES PATENT OFFICE

LESLIE E. SCOTT AND ERNEST A. SMITH, OF SAN JOSE, CALIFORNIA

AUTOMATIC VENDING MACHINE

Application filed August 29, 1930. Serial No. 478,658.

This invention relates to automatic vending machines and principally to one especially designed to handle and vend single blocks of ice of a certain size. It is customary for ice companies at certain seasons to conduct a retail cash and carry business, the customers calling at the warehouse or other supply house for their ice, which is now delivered to them by a salesman who must be constantly at hand to take care of their needs. This, of course, entails a considerable expense to the ice companies which the volume of business sometimes does not warrant.

The principal object of our invention is to provide an apparatus adapted to be installed in connection with an ice supply house by means of which a customer, upon depositing a certain amount of money, will have a block of ice of corresponding value automatically delivered to him, or moved to such a position as to enable him to easily manipulate the block of ice away from the premises. The need of an individual salesman is therefore avoided and it is only necessary for the workers in the supply house to occasionally replenish the supply of ice blocks in the machine as they are dispensed.

A further object of the invention is to construct the machine so that while it will hold a goodly supply of ice, it is compact and occupies but little space in a horizontal direction, and the saving of such space is usually quite essential or desirable.

It is also an object of the invention to vend blocks of wrapped ice from the conveyor portion of the machine by means of a roller apron extending from the machine through a wall of the storeroom or icehouse to a point of delivery outside the same.

A further object of the invention is to provide a simple and inexpensive device, and yet one which will be exceedingly effective for the purpose for which it is designed.

These objects we accomplish by means of such structure and relative arrangement of parts as will fully appear by a perusal of the following specification and claims.

In the drawings similar characters of reference indicate corresponding parts in the several views:

Fig. 1 is a side elevation of our improved vending machine.

Fig. 2 is a front elevation of the machine with the front apron removed.

Fig. 3 is a fragmentary and more or less diagrammatic view showing the ice controlled switch opening member. 55

Fig. 4 is a diagram of the operating circuit of the machine.

Referring now more particularly to the characters of reference on the drawings, the machine comprises a horizontal frame structure 1 which supports the end rollers 2 of an endless belt 3, on the upper run of which a certain number of blocks of ice 4 are supported. One roller is adapted to be driven by an electric motor 5 by suitable driving connections therebetween which may be of any desired character. The roller and the belt are driven so that the upper run of the latter moves toward the forward end of the machine, from which end a downwardly sloping roller apron 6 depends. This apron projects through an opening 7 in the front wall 8 of the building in which the machine is mounted and extends outwardly of the building a sufficient distance to support a block of ice when the latter is fully outside the building. 70

Pivoted at its upper end on a switch-box 9, which is mounted above the rear end of the apron at a height greater than the height of an ice block, is a forwardly projecting and substantially horizontal arm unit 10. This unit tends to drop of its own weight but is prevented from so doing beyond a predetermined limit by a stop 11 of suitable character. When the arm is in this position, a finger 12 thereon, which extends inwardly of the switch-box, acts to hold the switch 13 closed, which switch tends to open of itself and is interposed in an auxiliary circuit A connected to the motor circuit C. When the arm is raised, the finger disengages the switch and the latter is opened. The closing of this switch alone, however, is not sufficient to completely close the motor circuit, it being necessary that another switch M be employed. 80

This latter switch is of the magnet op- 100

erated type, and is interposed in one side of the circuit C ahead of the connection of the circuit A with said side. The magnet of this switch is interposed in the auxiliary circuit A. The magnet will therefore not be energized even though the switch 13 is closed, unless the switch M is first closed. The initial energizing of the magnet necessary to thus close switch M is controlled by 10 a further switch S interposed in another auxiliary circuit B connected to the circuit A beyond the magnet and to the same side of the circuit C as that in which the switch M is interposed, and ahead of the same.

15 The switch S is coin controlled, and is mounted in a slot-box 14 positioned on the outside of the building convenient to the customer, and is of course adapted to receive a coin of the value corresponding to 20 that of the block of ice. By means of this arrangement it will be seen that upon the customer depositing a coin, the circuit to the motor is completely closed, since unless the arm 10 is engaged by a block of ice, the 25 switch 13 is closed. As soon, however, as the block being dispensed reaches the apron and tends to slide down the same, it engages the arm and opens the switch 13. Since the magnet of the switch M is held energized 30 by reason of the closing of said switch after the coin has passed by the switch S, as well as the closing of the circuit A, the breaking of said circuit A will of course de-energize the magnet and a subsequent reclosing of the 35 switch 13 will not again of itself reclose the switch S. Only one block of ice at a time, therefore, will be dispensed with the depositing of any one coin in the switch-box.

The outer end of the lever is adapted to 40 be engaged and raised by a block of ice as the latter leaves the belt and is received on the apron, as shown in Fig. 1, so that the motor circuit will be opened and the advance of the belt halted before another block of 45 ice is received on the apron. To enable this arm to be raised to a switch-opening position with blocks of different heights, said arm is made in two swivelly connected portions so that the outer end portion may be bent 50 up or down as may be necessary without disturbing the normal position of the upper portion. At the same time the two parts when once adjusted to position, are maintained in rigid relationship with each other, 55 a clamping screw 15 being employed as the swivel connection.

To enable the apparatus to hold a considerable number of blocks without a great length of belt, we provide a block-supporting 60 track 16 above the belt, which is supported from the frames 1 by an auxiliary framework which includes uprights 17. These uprights rest on the frames 1 and are mounted for limited vertical movement relative thereto 65 to depending pins 18 engaging said frames

1. The track slopes down toward the rear end of the belt substantially semicircular and concentric tracks 19 connecting the adjacent ends of the track 16 and the belt so that the blocks of ice can move without disengaging each other, during their transfer from the track onto the belt. The trackways 19 constitute inner and outer portions, the inner portion having its inception on a level with the upper track 16, while the outer portion having its termination on a level with the belt. The space between the trackways 19 is of course sufficient to enable the blocks of ice to move along the same without danger of jamming.

The blocks of ice are initially loaded as necessary onto the upper end of the track 16 and abut against each other. If they remain dormant for any length of time the blocks are of course apt to freeze together. To automatically break the blocks apart is necessary with the dispensing movement of each block, the following device is provided: Fixed on the shaft of the rearmost roller 2 is an eccentric pin 20 which intermittently engages one end of a horizontal lever 21 which is pivoted intermediate its ends in connection with the frame 1. At its opposite end the lever engages the lower end of one of the pins 18 so that with each revolution of the roller 2, an upward jarring movement is imparted to the adjacent upright 17. Such movement being somewhat sudden and being imparted only to one side of the structure jars and twists the track sufficiently to cause the ice blocks thereon to be disengaged from each other if they have frozen together somewhat. A definite separation of the adjacent faces of the blocks of course takes place when they reach the curved trackways and also when they leave the belt and pass onto the delivery apron. The apron 6 as shown is preferably of that type in which transverse rollers comprise the block supporting means, so that the movement of the block down the apron will be rapid and there will be no tendency for the block to lag when on the apron.

From the foregoing description it will be readily seen that we have produced such a device as substantially fulfills the objects of the invention as set forth herein.

While this specification sets forth in detail the present and preferred construction of the device, still in practice such deviations from such detail may be resorted to as to not form a departure from the spirit of the invention, as defined by the appended claims.

Having thus described our invention what we claim as new and useful and desire to secure by Letters Patent is:

1. An automatic block vending machine including a horizontal conveyor to support a row of blocks, an electric motor to drive the conveyor, a circuit for the motor including a switch, a pivoted arm above the plane of the

conveyor and adapted to be engaged and raised by a block leaving the conveyor, and means between the arm and switch for holding the latter closed except when the arm is thus raised; said arm comprising a pair of parts swivelly connected together for relative movement in a vertical plane whereby to permit of the engagement of said arm by blocks of different heights without altering the normal position of the upper portion of the arm.

2. In an automatic vending apparatus having a horizontal and movable conveyer adapted to support a row of blocks, a relatively stationary block supporting track, extending lengthwise of and above the conveyer and leading to the same at one end, a turntable member associated with the conveyer, means for driving the conveyer whereby said member will be rotated, an eccentric element projecting from said member, a vertically movable frame supporting the track, and a horizontal lever pivoted intermediate its ends, one end of the lever being positioned to be intermittently engaged and depressed by the element and the other end engaging the frame to then raise the same.

3. An automatic block vending machine including a conveyor to support a row of blocks, an electric motor for driving the conveyor, a main circuit for the motor, an automatic switch therein, an auxiliary circuit, a normally closed switch in said auxiliary circuit, a separate normally open switch in said auxiliary circuit, means actuated by a block leaving the conveyor to temporarily open said normally closed switch, and means interposed in the auxiliary circuit and actuated by the closing of both auxiliary circuit switches simultaneously to close the main switch; said auxiliary circuit being arranged to be then held closed until the block controlled switch is opened regardless of the intervening opening of the other auxiliary circuit switch.

45. In testimony whereof we affix our signatures.

LESLIE E. SCOTT.
ERNEST A. SMITH.
